UNITED STATES PATENT OFFICE.

EMANUEL B. ADLER, OF PITTSBURG, PENNSYLVANIA, ASSIGNOR TO HENRY ADLER, OF PITTSBURG, PENNSYLVANIA.

DESIGN FOR A GAS-STOVE FRONT.

SPECIFICATION forming part of Design No. 36,077, dated September 16, 1902.

Application filed August 9, 1902. Serial No. 119,142. Term of patent 7 years.

To all whom it may concern:

Be it known that I, EMANUEL B. ADLER, a resident of Pittsburg, in the county of Allegheny and State of Pennsylvania, have invented a new, original, and ornamental Design for a Gas-Stove Front; and I do hereby declare the following to be a full, clear, and exact description thereof, reference being had to the accompanying drawing, in which the figure illustrates a perspective view of a stove-front ornamented according to the design.

The reference-numeral 1 represents the front plate of a gas-stove, which is provided with the curved legs 2 thereon and provided with the curved ornamentation 3, as shown. A border 4 extends along the side edges of the plate 2 and along the top edges of the same for some distance and terminates in the curved inwardly-extending portions 4', while another border-line 5 extends around the opening 5' in the plate 1 and is provided with the curved upper portions 5". Between the curved border portions 5 are the initials H A in a monogram, and below the same is the ornamentation 6, while above the same is the ornamentation 7, having the diverging-ray ornament 8, extending above and outward from the same and provided with the scroll-

work 9 on each side connecting the top border 4. A cross-border 10 extends across the plate 2 between the side borders 4 and forms the bottom line of the opening 5', while extending down from and joining the curved legs 3 are the panels 11. The bottom 12 of the plate 2 is provided with the scrollwork 13 between the legs 3 and above which is the diverging ornamentation 14, connecting the same and the cross-border 10. The face of the plate 2 is ornamented with the diamond - shaped spaces 15 therein, which are provided with the raised centers 16 in the same, and rosettes 17 are formed on the face of the plate 2, adjacent to the border 4.

The leading features of this design reside in the general configuration of the stove-front as a whole and in the ornamentation thereof, as illustrated.

What I claim as my invention is—

The ornamental design for a gas-stove front, substantially as herein shown and described.

In testimony whereof I, the said EMANUEL B. ADLER, have hereunto set my hand.

EMANUEL B. ADLER.
